UNITED STATES PATENT OFFICE

154,971

DESIGN FOR A KNITTING NEEDLE

Ellen Williamson, Princeton, N. J., assignor to
Knitmark Inc., Princeton, N. J., a corporation
of New Jersey

Application November 23, 1948, Serial No. 149,795

Term of patent 7 years

(Cl. D47—5)

To all whom it may concern:

Be it known that I, Ellen Williamson, a citizen of the United States, residing at Princeton, New Jersey, have invented a new, original, and ornamental Design for a Knitting Needle, of which the following is a specification, reference being had to the accompanying drawing, forming part thereof in which,

Fig. 1 is an elevation on an enlarged scale of a knitting needle showing my new design,

Fig. 2 is a longitudinal section on the same scale through the needle taken at right angles to the view of Fig. 1, while,

Fig. 3 is a plan view of the needle.

The irregular masses in the head of the knitting needle are completely contained within said head.

I claim:

The ornamental design for a knitting needle, as shown and described.

ELLEN WILLIAMSON.
